MANUFACTURE OF CIGARETTES

William Frederick Maitland Edwards, Esher,
England, assignor to Filter Tips Limited,
London, England

Application June 14, 1937, Serial No. 148,212
In Great Britain February 3, 1937

10 Claims. (Cl. 131—39)

This invention relates to an improvement in or modification of the method and apparatus described and claimed in the co-pending application No. 63,803, filed February 13, 1936, for the manufacture of filter tip cigarettes.

In accordance with the aforesaid co-pending application cigarettes or lengths of cigarette rod and filter tips or stub portions are assembled in alignment and caused to abut axially by means 10 of fixed guides engaging the outer ends of the assemblages before application of the latter on to a conveyor such as a drum or endless belt whereby the assemblages with which uniting bands have been brought into contact are carried into engagement with a fixed or relatively moving member between which and the conveyor the assemblages are rolled so as to wrap the uniting bands therearound.

It has been found that in order to ensure consistent production of satisfactory products under ordinary factory conditions it is necessary or highly desirable to provide for maintenance of slight axial pressure towards one another of the lengths comprising each assemblage while the latter is undergoing the rolling operation so as to counteract the natural tendency of the assemblage elements to separate during rolling.

The present invention is particularly applicable for use with the embodiment or modification 30 of the apparatus shown and described in the aforesaid co-pending application wherein the conveyor is in the form of an endless belt and in which the rolling of the assemblages takes place between the belt and a stationary member.

35 The present invention has for its object, therefore, to provide a method and means whereby slight axial pressure may be applied to the lengths comprising each assemblage during the rolling operation without employing any guiding means engaging the outer ends of the assemblage and without any such high degree of axial pressure as would result in shortening or compression of the lengths constituting the assemblage.

The invention is hereinafter described by way 45 of example with reference to the accompanying diagrammatic drawings, in which:

Figure 1 is a side elevation of apparatus according to one embodiment of the invention;

Figure 2 is a plan view of the conveying means 50 shown in Figure 1;

Figure 3 is a side elevation illustrating a modification;

Figure 4 is a plan view of the conveying means shown in Figure 3; and

55 Figures 5, 6, 7 and 8 are cross-sections on the

lines V—V, VI—VI, VII—VII and VIII—VIII in Figure 4.

Figure 9 is a sectional view taken on line IX—IX of Figure 4.

In one embodiment, a conveyor is provided consisting of three endless belts 1, 2 and 2a arranged side by side. The central belt 1 preferably is perforated so that the uniting bands 4, previously coated with adhesive, may be retained thereon by suction and fed thereby up to the rolling position 10 at which the assemblages, each consisting of a double length stub portion 7 and two cigarette portions 8, 8a are transferred on to the conveyor from an assembling drum 5 or from a suitable transfer device, it being understood that before 15 application on to the uniting band carried on the central belt the lengths 7, 8, 8a comprising each assemblage have been pressed axially into abutting contact. The wrapping of the uniting bands 4 around the assemblages is effected by 20 rolling of the assemblages between the conveyor 1 and a stationary plate 6 in accordance with the aforesaid copending application.

According to the present invention the two outer belts 2, 2a are arranged so as to converge 25 towards the central belt 1 in the direction of movement and thus during the rolling operation these convergent belts 2, 2a will tend to press the outer parts 8, 8a of the assemblage towards one another and thereby ensure maintenance of 30 abutting contact with the stub portion 7 during the rolling operation. The three belts 1, 2, 2a are driven in unison and the two outer belts 2, 2a may be driven through universal joints or equivalent means so that the angle of convergence 35 may be adjusted as required.

As shown in the drawings, belt 1 is supported at one end by roller 1a and at the other end by another roller not shown. Roller 1a is mounted on a fixed frame 1b. Belts 2 and 2a are each 40 mounted on a pair of rollers 2b and 2c supported in a frame 2d which is constructed to pivot about point 2e.

In a modification, as illustrated in Figures 3 to 8, a single conveyor belt 9, preferably of a 45 width greater than the length of the assemblage, is utilised and during a part of its travel at which the rolling operation takes place the two outer or marginal portions of the belt 9 pass over substantially longitudinally extending grooves or 50 troughs 10, 10a in a suction table 11, such grooves or troughs 10a being of gradually increasing depth and/or width in the direction of movement of the belt 9 so that during the rolling operation the belt 9 is, by the action of suction, contracted 55

in the widthwise direction and, as shown in Figures 5 to 8, thereby tends to carry the outer parts 8, 8a of the assemblages inwardly towards the intermediate stub portion 7. The central portion 5 of the belt 9 is perforated for feeding the uniting bands 4 as before described.

The invention is particularly applicable to the uniting of assemblages each consisting of two cigarette lengths 8, 8a and an intervening double 10 length filter tip or stub portion 7, but is also applicable for uniting assemblages embodying single cigarettes and single filter tips, or embodying more than three parts united by the application simultaneously of two or more uniting bands.

15 What I claim is:

1. In the manufacture of filter tip cigarettes by uniting an assemblage of cigarette and mouthpiece stub portions in abutting contact by a uniting band, the steps comprising rolling the assemblage between relatively movable surfaces, and frictionally applying slight axial pressure to the portions of the assemblage in such manner as to maintain the abutting contact of such portions during the rolling operation.

2. In the manufacture of filter tip cigarettes by uniting an assemblage of cigarette and mouthpiece stub portions by a uniting band, the steps comprising rolling the assemblage between relatively movable surfaces, and displacing the outer 30 portions of one of said surfaces inwardly toward each other to produce a converging effect and to transmit by frictional engagement with said assemblage, a slight axial pressure urging the portions of said assemblage together during rolling.

3. An apparatus for uniting an assemblage of cigarette and mouthpiece stub portions by a uniting band, comprising relatively moving surfaces between which an assemblage and a uniting band are rolled, and means forming part of one 40 of said surfaces for urging the elements of said assemblage axially together during rolling.

4. An apparatus for uniting an assemblage of cigarette and mouth piece stub portions by a uniting band, comprising relatively moving surfaces between which an assemblage and a uniting band are rolled, and means for displacing the outer portions of one of said surfaces, which surface portions are in frictional engagement with the portions of said assemblage, toward each other 50 to converge as the surfaces move relatively and thereby frictionally exert an axial pressure on the elements of said assemblage to urge said elements together during the rolling operation.

5. An apparatus for uniting an assemblage of cigarette and mouthpiece stub portions by a uniting band, comprising relatively moving surfaces between which an assemblage and a uniting band are rolled, an additional moving surface in contact with said assemblage, said additional surface being positioned alongside and in the same plane as one of said moving surfaces, and means for displacing said additional moving surface along with and transversely toward said one moving surface lying in the same plane therewith to 60 frictionally exert an axial pressure on the elements of said assemblage urging said elements together.

6. An apparatus for uniting an assemblage of cigarette and mouthpiece stub portions by a uniting band, comprising relatively moving surfaces between which an assemblage and a uniting band are rolled, additional moving surfaces in contact with said assemblage, said additional sur-

faces being positioned on opposite sides of and in the same plane as one of said moving surfaces, and means for displacing said additional surfaces along with and transversely toward said one moving surface lying in the same plane therewith to frictionally exert an axial pressure on the elements of said assemblage urging said elements together. 5

7. An apparatus for uniting an assemblage of cigarette and mouthpiece stub portions by a uniting band, comprising relatively moving surfaces between which an assemblage and a uniting band are rolled, one of said surfaces comprising three conveyors arranged side by side, the central conveyor engaging the uniting band applied to the 10 assemblage, and the two outer conveyors, which support the outer parts of the assemblage, being arranged to converge towards the central conveyor. 15

8. An apparatus for uniting an assemblage of cigarette and mouthpiece stub portions by a uniting band, comprising relatively moving surfaces between which an assemblage and a uniting band are rolled, one of said surfaces comprising a conveyor belt of flexible material, and a suction table 20 for supporting said belt beneath the other of said surfaces, said table having troughs extending longitudinally of said table with suction openings in the bottoms thereof, the cross-section of said troughs increasing in the direction of movement 25 of said belt so that a greater portion of the belt will be drawn into said troughs as it travels over the table thereby causing the outer portions of said belt to contract toward each other during travel of said belt to frictionally urge the elements of said assemblage axially together. 30

9. An apparatus for uniting an assemblage of cigarette and mouthpiece stub portions by a uniting band, comprising relatively moving surfaces between which an assemblage and a uniting band 40 are rolled, one of said surfaces comprising three conveyors arranged side by side, the central conveyor engaging the uniting band applied to the assemblage, and the two outer conveyors, which support the outer parts of the assemblage, being 45 arranged to converge towards the central conveyor, said central conveyor being perforate, and a suction table associated with said central conveyor for conveying a uniting band to an assemblage. 50

10. An apparatus for uniting an assemblage of cigarette and mouthpiece stub portions by a uniting band, comprising relatively moving surfaces between which an assemblage and a uniting band 55 are rolled, one of said surfaces comprising a conveyor belt of flexible material, and a suction table for supporting said belt beneath the other of said surfaces, said table having troughs extending longitudinally of said table with suction openings in the bottoms thereof, the cross-section of said 60 troughs increasing in the direction of movement of said belt so that a greater portion of the belt will be drawn into said troughs as it travels over the table thereby causing the outer portions of said belt to contract toward each other during travel of said belt to frictionally urge the elements of said assemblage axially together, said belt having a central set of perforations and said suction table having suction openings adapted to cooperate with the belt perforations for conveying a 65 uniting band to an assemblage. 70
